J. R. SANDAGE

HEATER

Filed April 12, 1926

Inventor:
Jacob R. Sandage
By Arthur F. Durand
MOTORS

UNITED STATES PATENT OFFICE.

JACOB R. SANDAGE, OF CHICAGO, ILLINOIS.

HEATER.

Application filed April 12, 1926. Serial No. 101,254.

This invention relates to heaters of the kind in which air is taken in at the bottom and discharged in heated condition at the top of the heater, means of any suitable character, such as a gas burner or other heating element, being enclosed within the body of the heater, so that the air is heated as it passes upwardly inside the heater body.

10. This is an improvement upon the form of heater shown, described and claimed in prior application No. 46,062, filed July 25, 1925.

An object of the invention constituting the improvement is to provide a construction 15 in which the maximum heat will be at the front of the heater, while the minimum temperature will be at the back thereof, so that the heater may stand upright against or close to a wall, without danger of burning or overheating the wall.

Another object is to provide a novel and improved construction involving the use of flat walls practically throughout the entire structure, and to reduce the cost of manufacture.

It is also an object to provide certain details and features of construction, and combinations tending to increase the general efficiency and the desirability of a heater of 30 this particular character.

To the foregoing and other useful ends, the invention consists in the matters herein-after set forth and claimed, and shown in the accompanying drawings, in which,—

35 Fig. 1 is a front elevation of a heater embodying the features of the invention;

Fig. 2 is a vertical section on line 2—2 in Fig. 1;

40 Fig. 3 is a horizontal section on line 3—3 in Fig. 1.

As thus illustrated, the body of the heater comprises flat, upright front and back walls 1 and 2, and the flat side walls 3, forming a hollow, upright body having a flat top wall 4 and a flat bottom wall 5, as shown. Said top wall is provided with air outlets 6, and the said bottom wall is provided with air inlets 7 and 8, as shown. The flue 9 extends upwardly within the body, and is inclined toward the front of the body, as shown. This flue forms a hollow partition within the body, dividing the interior of the body into a front compartment 10 and a rear compartment 11. As shown, the said flue is open at its upper and lower ends, and its front wall is provided with inlet open-

ings 12 near the top of the front compartment. A flat top plate 13 is provided, being mounted upon the upper ends of the angle-iron corner members 14 of the body, with 60 space between this plate and the top wall 4, and with the rear portion of said plate turned down to form the back wall 15, whereby the space between the plate 13 and the wall 14 is open at the front of the heater and also at each side thereof, but not at the rear. The said angle-iron members 14 are extended downward below the body of the heater to form the legs 16 thereof. A baffle plate 17 is preferably provided a distance 70 below the bottom wall 5 of the heater, so that air may enter the lower end of the flue 9, and also through the openings 7 and 8, in the manner indicated by the arrows. A gas burner 18, or any other heating element, is 75 preferably provided, as shown, in the front compartment 10, near the lower end of the flue, whereby the air in the flue will be highly heated by the transmission of heat through the front wall of the flue, and whereby the air entering the compartment 10 at the bottom thereof will be heated, and will be discharged, with any gases or products of combustion, from the top of the front compartment through the openings 12 80 into the upper end of the flue.

Thus the air entering the bottom of the flue, and the air entering the bottom of the compartment 10 is all finally brought together and commingled in the space between the wall 4 and the plate 13, and then discharged laterally from said space. Also, the air entering at the bottom of the compartment 11 will be heated in this compartment, and will escape, through the opening into 90 the mixing or commingling space below the plate 13, in a manner to practically insure a good quality of heated air. But the heat in the compartment 11 will be much less than that in the front compartment 10, of course, and in this way the heater will practically have a cool back which can stand against a wall without danger of burning or overheating the wall.

Of course, the flue 9 extends from one side wall 3 to the other side wall 3, so that the compartments 10 and 11 are non-inter-communicating. As the flue is inclined toward the front of the heater, it follows that the front compartment tapers upwardly, 100 while the rear compartment tapers downwardly.

A small swinging door 19 is provided, of any suitable character, to permit access to the interior of the heater to light the gas, or for any other purpose.

5. Also, the front of the heater preferably has a transparent or translucent window 20, in front of the burner or other heating element.

Without disclaiming anything, and without prejudice to any novelty disclosed, what 10 I claim as my invention is:—

1. In a heater for receiving air at the bottom thereof, and for heating the air therein, and for then discharging the heated air from the top thereof, the combination of a body 15 forming outer side walls and a back wall and a front wall for the heater, an open bottom flue extending upward therein, an imperforate top plate for the heater, with space between the outside of said flue and the inside 20 of said body, the heater having inlet means at the base thereof to admit air to the lower end of said flue, and also to the bottom of said space, the flue having one or more inlet openings in the upper front portion 25 thereof to receive the heated air from the upper portion of said space, so that the flue and space intercommunicate, and the upper portion of said heater having means disposed above the top of said space and below said top 30 plate for commingling and for laterally discharging all of the air which enters the heater at the bottom thereof, and which passes upward both inside and outside of said flue, in combination with a heating element applied to the lower portion of said flue, in position to heat some air directly and some 35 through the wall of the flue, said flue forming a hollow partition wall within said body, dividing the interior thereof into a front 40 compartment and a rear compartment, preventing communication from one compartment to the other, but with said intercommunication between said front compartment and said flue, and said heating element being in said front compartment, whereby the 45 maximum heat will be in the front compartment and the rear compartment will be comparatively cool, to permit the back of the heater to stand against or close to a wall.

50 2. A structure as specified in claim 1, said flue being inclined forwardly, so that it overhangs the heating element, and is closer at the front wall of the front compartment at its upper end than at its lower end.

55 3. A structure as specified in claim 1, said

rear compartment having an air inlet opening at the bottom and an air outlet opening at its top, and the rear imperforate wall of the flue forming the front wall of the rear compartment.

60 4. A structure as specified in claim 1, the front and rear and side walls of the body being flat, the body having flat top and bottom walls, the flat top wall being disposed a distance below said top plate, and the space 65 between the top wall and the top plate being closed at the rear thereof, but open at the front and at both sides of the heater.

5. A structure as specified in claim 1, said 70 flue being flat and having parallel front and back walls, and the flue being open at its upper end to discharge the air from the front compartment upwardly into the space immediately below said top plate.

75 6. In a heater, a body forming the outer front and rear and side walls of the heater, a flue therein dividing the interior of the body into front and rear non-intercommunicating compartments, the flue being open at its upper end and also at its lower end, 80 means to admit air at the bottom of each compartment, means to discharge the air from the top of the rear compartment, means to discharge the air from the upper portion 85 of the front compartment into the upper portion of the flue, so that all air entering the front compartment must escape from the top of said flue, and a heating element in the front compartment.

90 7. A structure as specified in claim 6, and a plate disposed a distance above the top of said body, forming a space below said plate for receiving and mixing the air discharged from the top of the rear compartment and from the upper end of the flue and front 95 compartment.

100 8. A structure as specified in claim 6, said flue being flat and forming a hollow partition extending from one side wall of the body to the other, and inclined forwardly, 100 whereby the front compartment tapers upwardly, while the rear compartment tapers downwardly, the rear imperforate wall of the flue forming the front wall of the rear compartment, and the front perforate wall 105 of the flue forming the rear wall of said front compartment.

Specification signed this 9th day of April, 1926.

JACOB R. SANDAGE.
